UNITED STATES PATENT OFFICE

ANDREW A. KRAMER, OF KANSAS CITY, MISSOURI

FLOATING-DECK TANK

Application filed April 1, 1927. Serial No. 180,242.

My invention relates to tanks and more particularly to floating deck tanks, or tanks having decks supported by the liquid within the tank and moving up and down with the 5 level of said liquid.

It is a purpose of my invention to provide a tank of the above mentioned character wherein the contents of the tank are effectively sealed off from the outer air, this being very desirable for fire prevention purposes. This is accomplished by suitable sealing means provided between the circumferential edge portion of the deck and the side wall of the tank, said deck being of 10 somewhat smaller diameter than the tank to permit the insertion of the sealing means therebetween. My invention contemplates the use of new and improved sealing means not only preventing the escape of liquid, but 15 also the escape of volatile matter from within the space in the tank under the deck. As this volatile matter is a very valuable ingredient of oil, the material stored in tanks of this character, this is a very important 20 feature of the invention.

It is a further purpose of my invention to provide new and improved means for preventing the deck from rotating within the tank, this being highly important, as it prevents 25 undue strain on parts associated with the deck, such as the drain line leading therefrom.

It is still a further purpose of my invention to provide means for draining water 30 from the deck, comprising a well on the deck and a drain line leading therefrom, said drain line adjusting its position in accordance with the position of the deck; and to furthermore provide means preventing the 35 flow of liquid onto the deck from said well or drain line, but permitting the flow of liquid from the deck into the well and drain line.

It is another purpose of my invention to 40 provide means for supporting the deck in a predetermined spaced relation from the bottom of the tank for cleaning purposes, said means comprising flexible members engaging the top edge of the tank and flexible 45 members engaging a central member.

It is also an object of my invention to provide new and improved means for properly guiding the up and down movements of the deck in the tank, comprising a central guiding member in the form of a post, and a 55 sleeve-like member slidably engaging therewith carried by said deck. Said guiding means are so related that the deck is free to move from a point near the bottom of the tank, to such a point that the tank may be 60 completely filled with oil or other liquid.

Other objects and advantages of the invention will appear as the description of the drawings proceeds. I desire to have it understood, however, that I do not intend to 65 limit myself to the details of construction shown or described, but that I intend to include as part of my invention all such obvious changes and modifications of parts as would occur to a person skilled in this art, 70 and as would fall within the scope of the claims.

In the drawings:

Fig. 1 is a vertical sectional view through a tank having my improved deck associated therewith, said deck being shown as being 75 held in spaced relation from the bottom of the tank for cleaning purposes.

Fig. 2 is a view similar to Fig. 1 showing the deck in full lines near the uppermost 80 limit of its movement and in dotted lines at the lowermost limit of its movement.

Fig. 3 is a fragmentary enlarged sectional view of the upper portion of the central supporting member for the deck. 85

Fig. 4 is a fragmentary plan view of the deck, partly broken away.

Fig. 5 is a view partly in elevation and partly in section of a portion of the collapsible ladder member and adjoining portions 90 of the tank.

Fig. 6 is a side elevational view of the drainage means for the deck.

Fig. 7 is a plan view thereof.

Fig. 8 is a section taken on the line 8—8 95 of Fig. 6 on an enlarged scale.

Fig. 9 is a fragmentary enlarged vertical sectional view through the sealing means between the tank and deck, showing adjoining portions of the deck and tank, and 100

Fig. 10 is a fragmentary face view of a plurality of the sealing means as viewed from the line 10—10 of Fig. 9.

Referring in detail to the drawings, my improved floating deck construction is applied to a tank having a bottom 20 and a side wall portion 21. Mounted on the bottom 20 of said tank is a plate 22, upon which the I-beams 23 are mounted, said I-beams supporting the plate 24, which is secured to the lower end of the tubular member 25 by welding the same to the collar 26 having screwthreaded engagement with said tubular member 25. The member 25 serves as a central post-like guiding member, and its upper end is provided with a collar 27 screwthreadedly engaging with said member 25 and having a ring-like member 28 secured thereto in any suitable manner, as by welding. The ring-like member 28 is provided with openings 29 receiving the hook-like members 30 provided on the ends of the flexible members, such as cables 31, which have their outer ends secured to the brackets 32 provided on the side wall portion 21 of the tank near the top thereof, and projecting above said top. In order to provide for the adjustment of the flexible members 31, so as to properly center the tubular center pole 25, the turnbuckles 33 are preferably interposed between the brackets 32 and the flexible members 31. It is, of course, to be understood, that the holes 29 and the brackets 32 are equidistantly spaced around the ring 28 and the top edge of the tank, to thus space the flexible members 31 substantially equally around the tank.

Slidably mounted on the central tubular member 25, is a tubular sleeve-like member 34 to which the radially extending members 35 of the deck framework are secured. Said members 35 are secured to the tubular member 34 preferably by welding, and, in order to provide a strong joint between said members the triangular plates 36 are welded to the member 34, and a ringlike member 36', said members 35 being welded to the ringlike member 36'. Interposed between the radially extending members 35, which extend all the way from the sleeve 34 to the outer edge of the deck, are shorter radially extending frame members 35', all said members being tied together by transverse members 37, which may be of any desired cross sectional shape. Mounted on the frame thus formed, are the deck plates 38. In order to provide a stronger joint between the deck and sleeve 34, the conical member 39 is welded both to the deck plates 38 and the sleeve 34. The members 35 and 35' preferably slope slightly toward the center of the deck, so that in a tank one hundred fifteen feet in diameter, for example, the deck will be about four inches lower at the center thereof than at the circumferential

edge thereof. The members 35 have brackets 40 secured thereto by any suitable securing means 41, to which the bifurcated ears 42 on the deck bracing rods 43 are secured. The opposite ends of said rods are secured to brackets 44 on the sleeve-like member 34 and are provided with turnbuckles for adjusting the same. Braces 45 may also be provided between the deck and the rods 43 to avoid sagging thereof, if desired.

Depending from certain of the members 35 are leg members 46, 47 and 48, the members 48 being located near the outer circumferential edge portion of the deck, and the members 46 and 47 being located nearer the center thereof. Each of said leg members is provided with a foot portion 49, which is adapted to engage the bottom 20 of the tank, to support the deck on said bottom, when the tank is emptied. Preferably diagonally extending braces 50 are provided between the members 47 and the deck.

Secured to the members 35 and 35' at the outer ends thereof, is the circumferentially extending channel member 51, depending from said deck, and in spaced relation to the side wall 21, the circumferential edge portion 52 of the deck being also spaced therefrom, thus leaving a gap, that must be closed to provide a complete seal between the contents of the tank under the deck and the outer air. It is, of course, understood that the deck constructed as described above forms a sheet-like member floatable on the liquid in the tank so as to move up and down with the change in level of the liquid in said tank.

The means for sealing the gap thus left between the tank and deck to permit free movement of the deck within the tank comprises shoes 53, which are arcuate in form, and which are hinged loosely at their lower ends on the flange 54 on the channel 51. Said shoes are provided with ears 55 extending through slots 56 in the flange 54 and held in position by any suitable means such as the cotter pins 57. The shoes 53 are thus free to swing about their lower ends, and are accordingly held in sliding engagement with the wall portion 21 of the tank at all times due to the action of gravity.

Extending upwardly from the deck plates 38 at the circumferential edge portion of the deck is an inwardly inclined flange 58 which has a base flange 59 secured to the deck in any suitable manner, as by welding. The shoes 53 are each provided with a pair of hooks 60, which are adapted to pass through slots 61 in the sheet metal basket members 62, which are dished downwardly so as to form containers for loose material 63, such as gravel. The ends of the basket members 62 opposite the ends supported by the shoes 53 are curved on a longer radius

as indicated at 64, and terminate in slightly inturned end portions 65, said basket members slidably engaging with the inclined flange 58. The shoes 53 are provided with flanges 66 at the edges thereof, and are slightly spaced so as to provide for the free individual movement thereof, whereby the same will always be free to engage with the tank wall 21. The basket members correspond in number and in width to the shoes, there being one basket member associated with each shoe, and there are, accordingly, gaps between the basket members. In order to keep the loose material 63 from falling through the spaces between the basket members 62, strips of reticulated material, such as hardware cloth 67, are placed over the spaces between the basket members, overlapping the adjoining basket members 62 and having meshes of such size as to prevent the loose material 63 from dropping through the same. In order to provide a more gas-tight seal than would be possible with the loose material 63 alone, fibrous sheet material 68 is employed in conjunction with said loose material. Said fibrous sheet material is, preferably, arranged in a series of overlapping lengths around the periphery of the deck, on top of the loose material 63, after a portion of said loose material has been put in the trough formed by the baskets 62 and members 67, and after said sheets 68 of fibrous material are put in place, the remainder of the loose material 63 is put in place, the fibrous sheet material thus being embedded in and held in place by said loose material. The fibrous material 68 preferably comprises an asbestos composition, which is coated with a suitable composition that is waterproof and which is not attacked by sulphur compounds given off by the oil in the tank.

The upper ends of the shoes 53 are provided with inturned flanges 69 to which either the members 70 or 71 are secured by securing devices 72. The members 70 and 71 alternate, and each thereof is associated with an individual shoe 53. The members 70 are provided with upturned side flanges 73 which coincide substantially with the side edges of the shoes upon which the same are mounted, while the members 71 are wider than the shoes carrying the same, and thus bridge the gaps between said shoes, resting on the flanges 73 of the members 70. In order to prevent binding of the members 71 on the flanges 73 suitable spacing means 74 are inserted between the members 71, and their shoes 53. The lower ends of the members 70 rest on the free edge portion 75 of the inclined flange 58 and are slidably thereover to permit adjustment of said members 70 and 71 in accordance with the positions of the shoes 53 carrying the same. The members 70 and 71 constitute water deflect-

ing means, whereby the water is directed away from the space between the deck and tank wall, and onto the deck. Said members 70 are also preferably provided with flanges 76 to prevent water from being driven under the same.

As stated above the deck slopes so as to be lower near the middle thereof than at the periphery thereof, and suitable drainage means is provided near the center of the deck, for draining the water off the same and conducting the same to a point outside the tank. Said drainage means comprises a drain well 77, which is shown more in detail in Figs. 6 to 8 inclusive. Secured to the top edge of the drain well 77 are angle members 78 forming an outwardly extending flange around said member 77 whereby the same is secured to the flanges 79 on certain of the adjoining frame members 35 of the deck. The well 77 is preferably tapered to fit between said members 35 as shown in Fig. 7. The drain well 77 is mounted in a suitable opening in the deck, and is provided with a threaded opening 80 in one of the side walls thereof, near the bottom of said well with which the threaded end 81 of a swivelled coupling member 82 is connected. Said coupling further comprises a coupling member 83 within which the member 82 may turn, said member 83 being held in assembled relation with the member 82 by means of the plate 84 and having an internally threaded end 85 with which the externally threaded end of the elbow 86 is engaged. Said elbow 86 is connected with a pipe 87 having an elbow 88 on the opposite end thereof connected by means of a similar swinging coupling 89 with the elbow 90 carried by the pipe 91. The pipe 91 has an elbow 92 at its lower end connected by the swinging coupling 93, with the horizontal pipe 94. The horizontal pipe 94 preferably is provided with a collar 95 for spacing the same slightly from the bottom of the tank and is screwthreadedly engaged with a coupling 96 welded as indicated at 97 to the tank wall 21 and passing through the same so as to make a liquid tight joint therewith.

Thus the water from the deck is adapted to flow off into the drain well 77 and through the drain line comprising the pipes 87, 91 and 94 swingingly connected together, and out through the side of the tank to a point outside the same, said drain line due to the provision of the swinging couplings being adapted to adjust itself to any position the deck may assume between the top and bottom of the tank. Means is furthermore, preferably provided whereby liquid is prevented from flowing from the drain well 77 onto the deck, but permitting the free flow of liquid from the deck into the drain well 77 and down the drain pipe. This is done so as to prevent the accidental flow

of oil or other liquid onto the deck due to leakage of the drainage means.

In order to prevent such backward flow of liquid from said drainage means onto the deck, a valve seat member 98 having a seat 99 for the ball valve 100 is provided. The valve seat member 98 is mounted on a plate 101 secured to the drain well 77 by means of angles 102, said member 98 being secured 10 to the plate 101 in any suitable manner, as by welding. The valve member 100 is mounted in a valve cage 103 having threaded end portions 104 with which the nuts 105 engage to hold the valve cage in position in the drain well. Ordinarily liquid is free to flow downwardly through the opening 106 into the well 77, but in case there is an upward flow of liquid in said well, the ball 100 will rise and move into engagement 15 with the seat 99, closing the opening 106 and preventing the flow of liquid upwardly through the same.

Means is provided for obtaining access to the deck over the top of the tank no matter 25 what the position of said deck may be within said tank. Said means comprises a ladder having a pair of tubular side members 107, which are secured in fixed position in the tank, by being secured thereto at the lower and upper ends thereof. The lower ends of the side members 107 are secured to the bottom 20 of the tank, by welding the flanges 108 carried by the lower ends of the members 107 thereto. The upper ends of the 30 side members or rails 107 are provided with elbows 109, substantially horizontally extending members 110 and elbows 111, whereby said members are carried over the top edge of the side wall portion of the tank, 35 and are further provided with depending tubular members 112 extending on the outer side of the wall portion 21 and secured thereto. Mounted on the tubular members 107 so as to be slidable along the same are 40 the collars 114, to which the treads or steps 116 of the ladder are secured by any suitable fastening devices.

The tubular side members 107 extend 45 through openings 124 in the deck and slidably engage with the tubular members 125 secured to the deck in any suitable manner, as by welding, said members 125 being reinforced by the conical members 126 welded to the deck and to said members 125.

50 Due to the fact that the tubular members 107 are slidably engaged with openings in the deck, and are fixed in position relative to the tank, the deck is held from rotation within the tank thereby. This is very desirable, as it prevents undue wear on the sealing means between the deck and tank, and also any disarrangement thereof due to such rotation. Furthermore any strain on such devices as the drain line secured to both the 55 deck and tank is prevented due to the fact

that the deck is held against rotation in the tank.

It is sometimes desirable to obtain access to the tank below the deck, for cleaning and other purposes, and in order to accomplish this, a manhole 127 having a cover 128 is provided in the deck. In order to hold the deck in spaced relation from the bottom of the tank, so as to permit a man to enter the space below the deck, when there is no liquid 70 therein, the flexible supporting members 129 and 130 are provided. These are secured respectively to brackets 131, secured to the members 35, and the brackets 40, previously described, at their lower ends. The flexible members 130 are provided with hooks 132 at their upper ends detachably engageable with the top edge of the side wall 21 of the tank, and the flexible members 129 are provided with hooks 133 engaging in equidistantly 75 spaced openings 134 in the plate 28. When the deck is to be released so as to permit the same to move up and down with the level of the liquid in the tank, the hooks 132 and 133 are disengaged and the flexible members 129 and 130 are preferably coiled around the brackets on the deck to which they are attached.

The deck is ordinarily slightly below the level of the liquid in the deck, indicated by 80 the numeral 135 in Fig. 9, but the top edge of the flange 58 is a considerable distance above the level of said liquid, the deck thus constituting a shallow panlike member floating on said liquid.

Having thus described my invention, what I desire to claim and secure by United States Letters Patent is:

1. The combination with a tank, of a floating deck therefor and drainage means for 105 said deck comprising a drain well carried by said deck, a drain line extending therefrom and means associated with said well permitting the flow of liquid from said deck into said well and preventing the flow of liquid 110 from said well onto said deck.

2. The combination with a tank, of a floating deck therefor and drainage means for 115 said deck comprising a drain well carried by said deck, a drain line adjustable in accordance with the position of said deck leading from said well to a point outside said tank and means associated with said well permitting the flow of liquid from said deck into said well and preventing the flow of liquid 120 from said well onto said deck.

3. The combination with a tank, of a floating deck therefor and valved drainage means for said deck permitting flow of liquid into the same from said deck but preventing flow of liquid from said drainage means onto said deck.

4. The combination with a tank, of a deck 125 smaller than said tank and movable therein and means for closing the space between the 130

wall of said tank and said deck comprising a plurality of sealing members mounted on said deck engaging said wall, means for bridging the joints between said sealing members, loose material supported by said sealing members and fibrous sheet material co-operating with said loose material to provide a gas-tight seal between said deck and tank.

5. The combination with a tank of a deck smaller than said tank movable therein and means for closing the space between the wall of said tank and said deck comprising loose material, means on said deck for supporting said loose material and fibrous sheet material embedded in and co-operating with said loose material to provide a seal between said deck and tank.

6. The combination with a tank of a deck smaller than said tank movable therein, means for closing the space between the wall of said tank and said deck comprising a plurality of sealing members mounted on said deck engaging said wall, means for bridging the joints between said members, loose material supported by said sealing members and fibrous sheet material co-operating with said loose material to provide a gas-tight seal between said deck and tank, and means for preventing rotation of said deck relative to said tank.

7. The combination with a tank of a deck smaller than said tank movable therein, a plurality of shoes movably mounted on said deck and engaging the wall of said tank, basket members mounted on said shoes, means for bridging the joints between said members, loose material supported by said basket members and fibrous sheet material co-operating with said loose material to provide a seal between said wall and deck.

8. The combination with a tank of a deck smaller than said tank movable therein, a plurality of shoes movably mounted on said deck and engaging the wall of said tank and water deflectors mounted on said shoes comprising alternating flanged members and members overlapping said flanged members.

9. The combination with a tank of a deck smaller than said tank movable therein, a plurality of shoes movably mounted on said deck and engaging the wall of said tank and water deflectors mounted on said shoes comprising alternating flanged members and members overlapping said flanged members, said members being each associated with an individual shoe and relatively movable.

10. The combination with a tank of a deck smaller than said tank movable therein, an upwardly extending flange on said deck, a plurality of shoes movably mounted on said deck and water deflectors mounted on said shoes comprising alternating flanged members engaging said upwardly extending

flange and members overlapping and resting on said flanged members.

11. The combination with a tank of a deck smaller than said tank movable therein, an upwardly extending inclined flange on said deck, a plurality of shoes movably mounted on said deck and inclined water deflectors mounted on said shoes comprising alternating flanged members engaging said upwardly extending flange and members overlapping and resting on said flanged members.

12. The combination with a tank of a deck smaller than said tank movable therein, an upwardly extending inclined flange on said deck, a plurality of shoes movably mounted on said deck and inclined water deflectors mounted on said shoes comprising alternating flanged members engaging said upwardly extending flange and members overlapping and resting on said flanged members, said members being each associated with an individual shoe and relatively movable.

13. The combination with a tank, of a deck movable therein and means for draining water from said deck to a point outside said tank, comprising a drain line adjusting its position in accordance with the position of said deck, a drain well on said deck with which said drain line is connected and a check valve in said drain well.

14. The combination with a tank, of a deck movable therein and means for draining water from said deck to a point outside said tank, comprising a drain line adjusting its position in accordance with the position of said deck, a drain well on said deck with which said drain line is connected and a ball valve in said drain well preventing upward flow of liquid from said well onto said deck.

15. The combination with a tank, of a deck movable therein and means for draining the water from said deck to a point outside said tank, comprising a drain line adjusting its position in accordance with the position of said deck, a drain well on said deck with which said drain line is connected, a ball valve in said drain well and a valve seat in said well above said valve and between said well and deck.

16. The combination with a tank, of a deck movable therein and means for draining the water from said deck to a point outside said tank, comprising a drain line adjusting its position in accordance with the position of said deck, a drain well on said deck with which said drain line is connected, a ball valve in said drain well, a cage therefor, and a valve seat in said well above said valve and between said well and deck.

In testimony whereof, I hereunto subscribe my name this 8th day of March, 1927.

ANDREW A. KRAMER.
